UNITED STATES PATENT OFFICE.

WILLIAM L. R. EMMET, OF SCHENECTADY, NEW YORK, ASSIGNOR TO GENERAL ELECTRIC COMPANY, A CORPORATION OF NEW YORK.

SYSTEM OF SHIP PROPULSION.

1,176,668.

Specification of Letters Patent. Patented Mar. 21, 1916.

Application filed August 21, 1911. Serial No. 645,175.

To all whom it may concern:

Be it known that I, WILLIAM L. R. EMMET, a citizen of the United States, residing at Schenectady, county of Schenectady, State of New York, have invented certain new and useful Improvements in Systems of Ship Propulsion, of which the following is a specification.

This invention relates to systems of ship 10 propulsion by electricity and has for its object the provision of a system of such a character that a large amount of electric energy in the form of heat is capable of being dissipated in a rapid and efficient manner through the agency of any suitable supply of water, such as sea water.

In my previous application, Serial No. 529,577, I have described and claimed an electrical system of ship propulsion embodying the use of electric generators and motors. In systems of this character it is necessary to employ electrical resistances which at times become excessively hot. This is especially true upon the reversals of the motor, 25 although the arrangement may be such that the resistance is in circuit and becomes hot at other times.

One of the objects of my invention is to provide such a system in which provision 30 is made for dissipating this excessive heat energy in a thoroughly safe and reliable manner. In my Patent No. 1,062,900, May 27, 1913, I have described and claimed a resistance suitable for the purpose above described.

My present invention relates more specifically to a system of ship propulsion embodying resistances cooled by circulating water.

40 In the accompanying drawing illustrating my system of ship propulsion, Figure 1 is a section through the hull of a ship showing the propeller shafts and the water cooled resistances; Fig. 2 is an enlarged view 45 of the water cooled resistance connected to the side of a ship; and Fig. 3 illustrates the general arrangement of the parts of the system and the circuit connections.

Referring first to Fig. 3, it will be seen 50 that my system involves the use of a generator G driven by a steam turbine T. The

particular type of turbine forms no part of my invention, and for purposes of illustration I have shown one in a conventional way having a valve B for controlling the admission of steam and an exhaust pipe X. This turbine is direct connected to the generator G which is excited from the direct current supply circuit D. The generator which I have shown is of the three phase type and supplies current to the electric motor M. A reversing switch S is provided for reversing the direction of rotation of the motor. This motor I have illustrated as an induction motor having an external resistance R 60 arranged to be connected in circuit with its rotor through slip rings on the shaft. The resistance is either connected in circuit or short circuited by shifting the operating lever L. The motor is direct connected to the propeller shaft upon which the propeller P is mounted. In the operation of this system the resistance R will be short circuited during normal operation; that is, when the ship is running either ahead or astern. When 65 the propeller is to be reversed, however, especially if the reversal is to be sudden, a powerful torque must be exerted by the motor to overcome the inertia of the ship. In order to accomplish this the resistance R 70 is thrown into the rotor circuit. The result is that a heavy current traverses this resistance so as to heat the resistance. In order to increase the current which this resistance can safely carry, I provide means for carrying off the heat developed in the resistance. In accomplishing this result, I make use 75 of any available supply of circulating water, such as the sea water, and cause it to circulate over the resistance. After extracting the heat from the resistance element the 80 water may be caused to return overboard. In order that the resistance element may be cooled most effectively, it is essential that the water shall be in direct contact with the 85 resistance element. In providing a resistance which is to be cooled in this way, difficulties are encountered. It is obvious that the water surrounding the conductor furnishes a path of very low resistance in parallel with the conductor and tends to cause a bubbling 90 and the formation of steam at the conductor 95 and the formation of steam at the conductor 100

terminals, which not only tends to eat away the conductor at the points where the current flows into the surrounding water but also gives a continuously varying resistance 5 due to the formation of air bubbles and steam at these points. In my previous application above referred to, I have disclosed a water cooled resistance which is satisfactory for this purpose. In Fig. 2 of the present 10 drawings I have shown such a resistance arranged to be cooled by the circulation of sea water from the side of the ship.

Referring now to Fig. 2, it will be seen that the water cooled rheostat is connected to 15 the side of the ship through an intake valve 10 and an outlet valve 11. The rheostat is arranged for a three phase system although it is obvious that my invention is in no sense limited to this particular application. As 20 thus arranged for a three phase system, the rheostat consists of two headers or manifolds 12 and 13, the former being connected with the intake valve and the latter with the outlet valve. Between these two headers are 25 connected three casings 14, 15 and 16, one for each resistance. The construction of these three casings is the same, as is also the arrangement of the resistance within the casings. Each has a lower enlarged portion 30 of insulating material, and an upper contracted portion 18 of similar material. These two sections are secured together, as shown, so as to form a continuous duct or conduit. Tie rods 19 are connected between 35 the two headers so as to strengthen the structure and feet 20 are supplied upon the lower header for supporting the rheostat upon the floor. In the lower enlarged portion of each duct is a resistance conductor 21 40 consisting of a plurality of resistance spirals connected together so as to permit the free circulation of the water between the turns of the spiral and also between the various spirals. The particular material which I 45 employ for this purpose has a high resistance and may be safely run at a high temperature. Furthermore, it will not oxidize or corrode. For this purpose the resistance material described and claimed in the patent 50 to Dempster, 901,428, is well suited. I have found this material to be almost entirely non-corrosive and to successfully withstand long submersion in salt solution. It is furthermore very slightly affected by electrolysis. The resistance material is preferably 55 made in the form of a flat ribbon and wound into a spiral, as shown. The spirals are arranged transversely of the casing so that the flat side of the conductor is parallel with the 60 sides of the casing. This arrangement reduces the resistance to the flow of water and leaves no place for the accumulation of bubbles. These successive spirals are connected alternately at their inner and outer ends so 65 as to make the windings non-inductive. The

resistance element extends only through the enlarged portion of the casing and the upper portion is provided in order to increase the length of the path through which the electric current can leak through the water. In 70 order to further increase the resistance of the path the upper part of the casing is reduced in size, as above described. The upper casing is reduced in size by an amount approximately sufficient to compensate for 75 the space in the larger casing occupied by the resistance element so that the reduction causes no great impediment to the flow of water. By this arrangement a large amount of electric energy can be dissipated in a very 80 small space. As above stated, in the normal operation of my system this rheostat will not be in use. When, however, it is desired to reverse the ship, say, for instance, from full speed ahead to full speed astern, the 85 rheostat is connected in circuit with the rotor of the motor. The resistance is so designed that under these circumstances it will heat rapidly and a circulation of the water which is in the conduits will take place due 90 to the heating of the water in the lower section of the conduit. Cold water will therefore be taken in through the intake valve and the hot water will be discharged through the outlet valve 11. By this means a very 95 large amount of heat energy may be dissipated in a very short time, while the space occupied, which is necessarily limited on shipboard, is reduced to a minimum. This arrangement makes it possible to reverse the 100 propellers in a very effective manner without danger of overheating.

While I have described my invention as embodied in concrete form for purposes of illustration it should be understood that I 105 do not limit my invention thereto, since various modifications thereof will suggest themselves to those skilled in the art without departing from the spirit of my invention, the scope of which is set forth in the 110 annexed claims.

What I claim as new and desire to secure by Letters Patent of the United States, is,

1. In a system of electric ship propulsion, an alternating current generating unit, a 115 propeller driving induction motor electrically connected to said generating unit, a resistance adapted to be electrically included in the secondary circuit of said motor, an insulating duct surrounding said resistance, 120 and an intake pipe and a discharge pipe connected to said duct and communicating with the water outside the ship and arranged so that the heat generated in the resistance effects a circulation of water through said 125 duct.

2. In a system of electric ship propulsion, a polyphase alternating current generating unit, a propeller driving polyphase induction motor electrically connected to said 130

generating unit, a plurality of insulating ducts, an intake pipe and a discharge pipe connected to said ducts and communicating with the water outside the ship, and a resistance adapted to be electrically included in the circuit of each phase of the secondary winding of said motor, each resistance being arranged in one of said ducts and adapted

to effect by the heat generated therein a circulation of water through said duct. 10

In witness whereof, I have hereunto set my hand this 19th day of August, 1911.

WILLIAM L. R. EMMET.
